UNITED STATES PATENT OFFICE.

WILLIAM F. CUMMINGS, OF CHICAGO, ILLINOIS.

SIGNAL LAMP.

Application filed July 11, 1919. Serial No. 310,117.

To all whom it may concern:

Be it known that I, WILLIAM F. CUMMINGS, a citizen of the United States, residing at Chicago, in the county of Cook and 5 State of Illinois, have invented certain new and useful Improvements in Signal Lamps, of which the following is a specification.

The invention relates to signal lamps.

One of the objects of the invention is 10 to provide a knock-down signal lamp in which the parts are inter-changeable, and in which a selected number of luminous outlets, within its capacity, may be incorporated in the assembled lamp structure.

15 Where one or more highways cross a railway track, a warning signal is usually placed, consisting of a periodically displayed, gas or electric, flash light. In situations where two or more roads cross a railway track at different angles thereto, a lamp having an outlet within a plane radial from the source of light and parallel with the roadway path, is necessary for its greatest efficiency and to properly comply with the 25 statutory provisions.

It is manifest, therefore, that especially constructed lamps of a large variety, as now made, are called for to meet the many varied requirements.

30 When it is understood that a lamp, properly adapted for the purpose, should have a luminous outlet with a field of vision in line with each roadway, one for each side of the railway track, and such necessity is 35 requisite for each roadway crossing the track at a given point, the nicety of required adjustment will be realized.

In my improved lamp the luminous outlet, or lens carrying frame, may be located 40 at any point within the circumferential extent of the lamp so that any two luminous outlets may be placed and maintained in the main lamp frame at any desired degree of separation, after the lamp has been located 45 at the crossing on its support.

The structure is such that the proper location of the lenses may be determined by empirical tests, by visual observation from the respective roadways, and the several 50 lenses thereupon adjusted until the light fields properly correspond with the radial direction of the roadways.

The construction of my improved lamp is also such that the lens-carrying frames 55 may be placed in the main frame and circumferentially adjusted to their proper re-

spective locations and after they have been so adjusted, opaque filler blanks may then be placed between the lens-carrying frames and the parts finally secured together. By this 60 means, the lamp may be arranged to fit any circumscribed environment, without requiring an especially constructed lamp for the purpose. This results in a very satisfactory method of installment and large saving of 65 expense in the manufacture of the lamps, by duplication of parts, and the very large number of lamps required to be kept in stock when they are arbitrarily made to fit the varying conditions to be found in actual 70 practice.

Other, further and more specific objects of my invention will be readily apparent to persons skilled in the art, from a consideration of the following description, when taken 75 in conjunction with the drawings, wherein:

Fig. 1 is a central vertical section of one embodiment of my lamp.

Fig. 2 is a transverse section thru the 80 lamp.

Fig. 3 is a section, similar to Fig. 1, taken at right angles thereto, on line 3-3 of Fig. 2.

Fig. 4 is a transverse section, similar to 85 Fig. 2, showing three luminous outlets instead of two, as shown in Fig. 2.

Fig. 5 is an enlarged portion of a rod for connecting the upper and lower sections of the main frame together, showing parts in 90 section.

Fig. 6 is a perspective view of the lens-carrying frame; and

Fig. 7 is a filler, to be placed between the parts of the main frame and between the 95 lens-carrying frames.

In all the views the same reference characters are employed to indicate similar parts.

In the embodiment of my invention, as illustrated in the drawings, 10 is a flange, screw threaded, as at 11, to be mounted upon a pipe support 12, through which the wires 13 and 14 pass to a socket 15', in which is contained a lamp 16.

Of course, in so far as my invention is concerned, a gas light or light from any other suitable source may be employed, and it may be a periodical flash light or steady burning light, as desired.

The lamp casing, or housing, consists of the lower main frame part 15, secured to the

flange by screws 16', that also secure the receptacle 15' thereto. The part 15 provides a vertical rim 17, turned over at its top edge, as at 18, to lend strength to the structure 5 and on the outside of the rim 17 is a ring 19 having one edge inturned to leave a space or annular groove between the outer surface of the rim 17 and the part 21 of the ring 19. The outer edge 22 of the ring is 10 outturned to provide the flange 23. This leaves an annular space or groove between the ring and the flange 17, within which to insert the lens-carrying frames 24, and the fillers 25. The upper portion 26 of the main 15 frame comprises a top 27, having a down-turned vertical rim 28, provided with a series of ventilating apertures 29, especially when the lamp is to be used for gas, and an overlying ring 30, spaced away from the 20 apertures, but covering them so that water will not enter the interior of the casing. Near the lower end of the rim 28 is a ring 31 having its upper edge inturned, as at 32, and its mid-portion outturned and folded 25 upon itself, as at 33, to form a flange and its other edge 34 downturned and separated from the rim 28 to leave an annular space or groove for the insertion of the lens-carrying frames and the separators, or fillers. 30 The lens-carrying frames 24 each consists of the segment 35 curved properly to fit within the annular spaces between the rings 19 and 31 and the respective parts 15 and 26. Each of the lens-carrying frames has 35 an inturned and outturned edge 37, somewhat shorter than the part 35, and it also carries a tapered lens-holding rim 38. The lens 39 is held in the rim by a ring 40 secured in place by a screw 41 passing through 40 the two parts of the meeting terminals of the ring.

The fillers 25 each consists of a piece of tin, or other similar sheet metal, properly curved, and of standard length, but of variable width, that are to be placed within the annular grooves of the main frame part and the lens-carrying frames, as clearly shown in Figs. 2 and 4. If the space between the lens-carrying frames is less than 45 the width of the given number of fillers 25, the side edges of the fillers may be trimmed with shears until they exactly fit the space between the lens frames. The fillers 25 lie within the rabbet made by the inturned portion 37 of the lens-carrying frame, thereby making the entire casing or housing absolutely light proof, except through the luminous openings. Means for holding the lower portion 15 and the upper portion 26 50 of the main casing together, consists of the rod 42 having heads 43, one at each end, similar in construction, consisting of an outturned part 44, and an inturned part 45, separated sufficiently to admit the flanges, 55 the upper flange 33 and the lower flange 23, between the parts 44 and 45. An axially aligned hole is drilled for a screw 46, into the part 44, as at 47, and the screw is preferably sharp pointed, so that when it is tightened in position, it pushes part of the 70 rim or bead 33 into the perforation 47 which holds the separating bars 42 firmly and securely in place at any point on the respective rims. The rims or beads 23 and 33, extend uninterruptedly around the two major 75 portions of the casing and since the lens-carrying frames are to be located at varying points in the circumferential extent of the casing, the holding rods 42 are of such character that they may be located at any selected point, in contact with the respective rims.

In locating the lamp in the situation in which it is to be maintained, the bottom main portion 15, of the lamp casing, is 80 placed in position on the supporting pipe 12, as shown in Fig. 3, after which as many lens-carrying frames as are required for the particular situation, are placed between the main portion 15 and the main portion 26, of 85 the casing. Then the lens-carrying frames are rotated, in the main frame to the positions required, with respect to the varying conditions of the roadway. After the lens-carrying frames have been properly located, 90 so that the burning light within the casing can be distinctly seen from each of the approaching roadways, the lens-carrying frames are marked in their adjusted positions, then the top 26 is removed and fillers 100 or separators 25, that have been cut to the proper width are placed in the groove of the bottom frame 15, whereupon the upper frame 26 is returned to its former position and the rods 42 are placed in contact with 105 the rims 23 and 33, respectively, and held in place between the lens-carrying frames of the organized structure.

Now, from the foregoing description and the exemplification shown in the drawings, 110 it is manifest, to persons skilled in the art, that any number of luminous outlets may be placed in the main frame or casing of the lamp, and located in the manner described, at the proper angle, with respect to the railway track, and maintained in their adjusted positions by the fillers that are subsequently placed between adjacent luminous outlet frames and the assembled structure held together by the rods 42, that may be placed at 115 any convenient point within adjacent lens carrying frames.

Having described my invention, what I claim is:

1. A knock-down signal lamp casing having in combinative association an upper and a lower separable casing part, each part having uninterrupted circumferentially continuous means for holding the lens-carrying frame at any desired point of said means 125

and opaque filler blanks and a lens carrying frame to close the casing; an outwardly-projecting, circumferentially-continuous rim, carried by each of said casing parts 5 and two or more rods engaging said rims outside of the casing to hold the parts together.

2. A lamp casing having in combination an upper and a lower casing part, each 10 part having a circumferentially continuous groove within which lens carrying frames and intervening fillers are carried; lens carrying frames having curved ends inserted within said grooves respectively; intervening 15 opaque fillers having curved ends inserted within said grooves between the frames and in the same circumferential plane and rods engaging said casing parts outside of the frames and fillers to hold the 20 parts together.

3. A knock-down signal lamp having in

combinative association a casing providing a lower part with a circumferentially-continuous groove; an upper part, having a similar confronting groove; one or more 25 lens-carrying frames having an opening within which to mount a lens and having curved terminal ends for insertion in the respective grooves; fillers of substantially the same height as the lens-carrying frames and 30 having curved terminal ends for insertion in the grooves between the lens-carrying frames and rods having U-shaped ends between the members of which to receive projections from the said casing parts and a 35 screw, threaded thru the outer member of each said U-shaped part to engage said projections, to hold the casing parts together.

In testimony whereof I hereunto subscribed my name.

WILLIAM F. CUMMINGS.
